EXPLOSIVE CHARGE FOR THE CENTRAL TUBES OF SHRAPNEL-SHELLS.

1,308,345.

Specification of Letters Patent.

Patented July 1, 1919.

Application filed May 2, 1916. Serial No. 94,947.

To all whom it may concern:

Be it known that I, FRANCIS I. DU PONT, a citizen of the United States, residing at Wilmington, county of New Castle, and 5 State of Delaware, have invented a new and useful Improvement in Explosive Charges for the Central Tubes of Shrapnel-Shells, of which the following is a full, clear, and exact description, reference being had to the 10 accompanying drawings, which form a part of this specification.

The connection between the time fuse of a shrapnel shell and the bursting charge is generally a series of short cylinders of com- 15 pressed black powder. Each of these cylinders has a hole extending axially there- through. The object of this arrangement is to produce the quickest possible transmission of fire from the time fuse in the head of the 20 shell to the bursting charge in the base. The theory of operation of the device is that the hole remaining open, the flame will instant- 25ly pass through the column of pellets and fire the bursting charge without varia- 30tion in time of bursting being produced by the fire having to penetrate through a column of powder which may have become packed tight by its own inertia when the shrapnel shell is started in motion in the gun.

The practical way in which this works out is that there being eight cylinders or "pel- 35lets" (as they are called) and these being necessarily a somewhat loose fit in the central tube of the shell, it is nearly impossible to avoid having the cylinders nearest the bursting charge crushed, in the act of firing the shell from the gun, by the accelerating force acting against the inertia of the pellets 40 ahead of them. This plugs the central tube with powder resulting from the crushing of the rear pellets and causes variation in time of explosion of this shell.

I have discovered a certain way in which 45 this can be prevented and by which the accuracy sought by this method of connecting the time fuse with the bursting charge of the shrapnel shell may be fully realized.

In making my improved powder charge 50 the powder is pressed into a tube to be inserted into the central tube of the shell, in such a way that a hole is left in the center throughout the entire length of the connec- 55tion.

In this way the powder is so well sup- 55 ported in the tube that it cannot be removed by a pressure greater than that which it must sustain when the shell is fired from the gun.

Preferably, the solid powder, having a 60 moisture content of about three per cent., is mixed with a liquid having no solvent or chemical action upon the powder, and im- 65 miscible with water, preferably gasolene or a liquid of similar properties, and the mix- 70 ture is tamped into a thin metal cylinder, thereby not only consolidating the powder but also causing the larger volume of the gasolene to exude, and then drying the powder, at an elevated temperature, in the cyl- 75 inder to drive off the gasolene and moisture. In the drying operation it might be sup- 80 posed, from the action of other material under similar conditions, that the powder charge would shrink so that its diameter 85 would be reduced sufficiently to cause it to be readily slipped from the mold. If this would occur, it would produce a unitary charge having some real advantage over the present charge of a number of short pellets, 90 but it would not accomplish the main object of the present invention. As a matter of fact it is found that if any shrinkage occurs, it does not operate to reduce the di- 95 ameter of the charge, but on the contrary the powder charge, after the drying opera- 100 tion, is found to be so tightly packed within the container as to resist ejection. By utilizing the tubular container with the charge packed therein as a substitute for the string of separately formed pellets, the objects and advantages of my invention are attained.

In carrying out the process for manufac- 95 turing my improved charge I utilize prefer- 105 ably an apparatus constructed in accord- 100 ance with the accompanying drawings, in which—

Figures 1 and 2 represent an elevation, partly in section, of the entire apparatus, the upper part of Fig. 2 being a continua- 100 tion of Fig. 1. Fig. 3 a plan view of the lower and main part of the apparatus. Fig. 4 is a longitudinal sectional view of the finished product. Fig. 5 is a sectional view of the charge applied to a shrapnel shell. 105

The explosive powder, together with gaso- 110lene, is placed in a tank *a* containing a revo- luble stirrer *b*, whereby the powder may

be kept in suspension in the gasolene. The amount of gasolene or equivalent liquid added should be sufficient to cover the powder and render the mass capable of flowing. The amount will vary with the particular liquid used and it will also vary with other conditions; but, as an example, it may be stated that with the mixing operation conducted at a temperature of 20° C., 5 10 equal parts by weight of the powder and gasolene will be found efficient.

After the powder has been stirred into a condition of uniform suspension in the gasolene, the fluid mass is transferred, by 15 means of a centrifugal pump *c*, through a tube *d*, into a vessel *e*. At one end of the vessel *e* is an overflow chamber *f*, spaced from the vessel *e* by a wall *g*, over the top of which the liquid mass overflows so as to 20 maintain constant the level of the vessel *e*.

A pipe *h* conducts the overflow back to the mixing tank *a*. Within the vessel *e* is a stirrer *i*, which continuously agitates the mixed powder and gasolene, this being necessary to prevent settlement of the powder, 25 which would otherwise occur quickly.

Arranged along one side of the vessel *e* is a charging chamber *j*. The bottom of the chamber *j* is raised much above the level of 30 the bottom of vessel *e*. In operation, chamber *j* is in open communication with vessel *e*, so that the two form virtually a unitary charging chamber; but a gate *k* at the conclusion of the mold filling and tamping operation, 35 may be manually applied to separate the vessel *e* from the chamber *j*, thereby shutting off the flow of liquid to the latter.

The bottom of chamber *j* has a series of 40 openings or nozzles *y*, between each of which and a vertically movable holder *m* is confined a tubular container *n*, which is preferably of thin metal. Each holder is threaded in a support *z* secured to the frame of the apparatus.

Extending centrally through each holder *m* and along the axis of the tube *n* is a pin *o*. The upper end of this pin extends 45 through the base of a hollow plunger *p*, which is of a diameter, at its base, adapted to loosely fit the tube *n*. Each plunger *p* extends into a cylinder *r* and carries a piston head *s* which works in the cylinder. Each cylinder has pipe connections *t* and a valve *u* whereby it may be reciprocated hydraulically, pneumatically, or by steam. 50 The cylinders may be connected to one main at the top and to one main at the bottom and one valve will then operate them in unison. Hydraulic actuation presents decided advantages, 55 but it is of the utmost importance that no water should be allowed to reach the powder. Instead of using an ordinary stuffing box, I prefer to provide the piston bushing with an annular chamber *v* which is connected through a pipe *w* with a vacuum

pump, whereby any water that leaks from the cylinder will pass into the chamber *v* and be withdrawn through the pipe *w*.

On the down stroke of the plunger *p* the pin *o*, which is fixed, displaces a certain volume of air. An opening *x* in the wall of the plunger permits this air to escape and affords also an outlet for any liquid that may leak thereinto.

Assuming that the tank *a* and vessel *e* are 75 filled, the pump in operation, and the gate *k* positioned to exclude the flow of the mixed powder and gasolene into the charging chamber *j*. The pins *o* have been withdrawn and the holders *m* have been screwed down 80 to allow of the insertion of the tubes *n*. The tubes *n* are now placed in position and the respective holders *m* are screwed up to confine the tubes *n* against the nozzles *y*. The pins *o* are now positioned as shown in the 85 drawings, the plungers *p* are reciprocated, and the gates are removed.

At each uplift of the plungers, a certain amount of the mixture flows into the tubes *n* so as to fill them (say) to about one-sixth 90 of their capacity before the plungers, on their down stroke, enter the tubes and thereby close the mouths thereof. The plungers *s* each descend with sufficient force to tamp the explosive to the desired density, much 95 the larger portion of the gasolene being thereby exuded and forced upwardly out of the tubes *n* between the walls thereof and the plungers. This operation is repeated until the tubes *n* are filled. It will be understood 100 that the plungers are not carried into the tubes *n* a determinate distance, but that the force with which they are depressed is adjusted to give the pressure required to consolidate the powder to the desired degree, 105 the plungers then yielding upwardly. It will also be understood that the plungers operate independently, so that even when operated by the same valve each will exert its own pressure independently of whether 110 or not the amounts of powder in the tubes are exactly the same.

After the tubes *n* are filled, the gate *k* is replaced, the holders *m* lowered, the pins *o* removed, and the tubes *n*, now filled with 115 compacted powder, withdrawn. The powder cylinders 10 are dried at an elevated temperature (say about 110° C.), and the gasolene and moisture that has remained in the powder will be driven off. After the 120 drying operation the powder cylinders are of a density and cohesiveness corresponding to the separate short pellets now in use and remain tightly packed within the shells and cannot be removed therefrom by a pressure 125 exceeding that which it must sustain when the shell is fired from the gun.

In Fig. 5 is shown an ordinary shrapnel shell 11 with applicant's unitary powder charge, shown separately in Fig. 4, inserted 130

within the central tube of a shrapnel shell and connecting the time fuse 12 with the bursting charge 13 as hereinbefore described.

Having now fully described my invention, 5 what I claim and desire to protect by Letters Patent is:—

1. In a shrapnel shell, the combination with the central tube, of a unitary longitudinally perforated powder charge within and 10 extending substantially throughout the length of the tube.

2. In a shrapnel shell, the combination with the central tube connecting the time fuse and bursting charge, of a charge comprising a rigid tubular container within and 15 extending substantially the length of the tube and a unitary longitudinally perforated powder charge packed tightly within and extending substantially the length of the 20 container.

3. In a shrapnel shell, the combination with the central tube connecting the time fuse and bursting charge, of a charge comprising a rigid tubular container within and 25 extending substantially the length of the tube and a longitudinally perforated pow-

der charge within the container in such relation thereto as to resist crushing in the act of firing the shell from the gun.

4. In a shrapnel shell, the combination 30 with the central tube, of a unitary longitudinally perforated powder charge extending through said tube approximately the entire distance between the fuse and the bursting charge and a container inclosing 35 the powder charge throughout the latter's length and restraining the particles of the powder charge from moving outward from the axis of the charge whereby the perforation is maintained open during the propul- 40 sion of the shell from the gun.

5. A charge for the central tube of a shrapnel shell comprising a rigid tubular container open at both ends and a unitary longitudinally perforated powder charge 45 within extending throughout the length of the container.

In testimony of which invention I have hereunto set my hand, at Philadelphia, on this 27th day of April, 1916.

FRANCIS I. DU PONT.
